MOULDING FOR A BUILDING DIRECTORY UNIT

Stanley E. Weeks, 4650 Grosvenor Ave.,
Montreal, Quebec, Canada

Filed Sept. 22, 1969, Ser. No. 19,246

Term of patent 14 years

Int. Cl. D25—03

U.S. Cl. D13—6

The figure is a perspective view of a moulding for a building directory unit embodying my new design.

I claim:

The ornamental design of a moulding for a building directory unit, as shown.
